DESIGN FOR AN OVER-BED TABLE

William A. Hillenbrand, Franklin County, Ind.,
assignor to Hill-Rom Company, Inc., Batesville, Ind., a corporation of Indiana

Application January 30, 1943, Serial No. 109,392

Term of patent 14 years

To all whom it may concern:

Be it known that I, William A. Hillenbrand, a citizen of the United States, residing in the county of Franklin and State of Indiana, have invented a new, original, and ornamental Design for an Over-Bed Table, of which the following is a specification, reference being had to the accompanying drawing, forming a part thereof.

I claim:

The ornamental design for an over-bed table, substantially as shown.

WILLIAM A. HILLENBRAND.
